(57) **CLAIM**

The ornamental design for a press stud, as shown and described.

DESCRIPTION

FIG. 1 is a bottom perspective view of a press stud according to a first embodiment;

FIG. 2 is a top perspective view thereof;

FIG. 3 is a front view thereof;

FIG. 4 is a bottom view thereof;

FIG. 5 is a top plan view thereof;

FIG. 6 is a top perspective view of a press stud according to a second embodiment;

FIG. 7 is a bottom perspective view thereof;

FIG. 8 is a front view thereof;

FIG. 9 is a top plan view thereof;

FIG. 10 is a bottom view thereof;

FIG. 11 is a bottom perspective view of a press stud according to a third embodiment;

FIG. 12 is a top perspective view thereof;

FIG. 13 is a front view thereof;

FIG. 14 is a bottom view thereof;

FIG. 15 is a top plan view thereof;

FIG. 16 is a bottom perspective view of a press stud according to a fourth embodiment;

FIG. 17 is a top perspective view thereof;

FIG. 18 is a front view thereof;

FIG. 19 is a bottom view thereof; and,

FIG. 20 is a top plan view thereof.

The broken lines in the drawing are for illustrative purposes only and form no part of the claimed design.
